Primary Examiner — Richard E Chilcot(74) *Attorney, Agent, or Firm* — Birch, Stewart, Kolasch & Birch, LLP(57) **CLAIM**

The ornamental design for a bluetooth headset, as shown and described.

DESCRIPTION

1. Bluetooth headset

1.1 : Perspective

1.2 : Front

1.3 : Back

(Continued)

1.4 : Left

1.5 : Right

1.6 : Top

1.7 : Bottom

1 Claim, 7 Drawing Sheets
